WITNESS

W.W. Williams

INVENTOR

Frank F. Wright

Galph Burch
ATTORNEY

UNITED STATES PATENT OFFICE.

FRANK F. WRIGHT, OF AURORA, ILLINOIS.

EAVES-TROUGH STRAINER.

Application filed September 10, 1923. Serial No. 661,872.

To all whom it may concern:

Be it known that FRANK F. WRIGHT, citizen of the United States, residing at Aurora, in the county of Kane and State of Illinois, 5 has invented certain new and useful Improvements in Eaves-Trough Strainers, of which the following is a specification.

My invention relates to improvements in eaves troughs and has for its primary object 10 to provide means for filtering the rain water collected by the trough, prior to its discharge into the drain spout, to remove leaves, twigs and other foreign matter, so the same will not clog the drain spout. 15 A further object is to provide a conduit extending from the trough and having a strainer, so arranged the foreign matter collected will be cast-off the strainer by the flow of water, so as not to interfere with the passage of the water through the conduit. 20

Another object resides in the provision of a strainer having means to facilitate the washing of the foreign matter over the strainer, and means to assist the percolation 25 of the water through the strainer.

A further object is to provide a device of the above-mentioned character which is simple and durable in construction, reliable and efficient in operation and inexpensive to 30 manufacture.

Other objects and advantages of the invention will be apparent during the course of the following description.

In the accompanying drawing forming a 35 part of this specification and in which like numerals are employed to designate like parts throughout the same—

Figure 1 is a perspective view of my invention attached to an eaves trough,

40 Figure 2 is a detail perspective view of the same, and,

Figure 3 is a longitudinal sectional view of the same attached to a trough.

In the drawing, wherein for the purpose 45 of illustration I have shown a preferred embodiment of my invention, the numeral 5, designates a conventional type of eaves trough employed to collect the rain water cast off from the roofs of buildings and the like.

50 As clearly shown in Fig. 1, the trough is inclined and near its lower end a portion of the back side is cut away leaving an outlet opening 6, through which the water is discharged into the conduit 7 connected to the usual drain spout 8.

The body of the conduit 7, is substantially

U-shape having one end opened and joined to the outlet 6, by means of the flange 9 and rivets 10. The conduit extends downwardly at a sharp angle to the trough 5, the 60 lower end having a wall 11 and a discharge pipe 12, extending from the wall near the bottom which connects the conduit with the drain spout 8. A strainer 13 extends lengthwise of the conduit and is diagonally disposed therein, so the upper end is flush with the bottom of the trough 5 and the lower end is flush with the upper edge of the wall 11, resting on the inwardly projecting ledge 11' formed integral with the wall. Side 65 portions 14 are bent upwardly from the strainer being securely clamped by the bent upper edges 15 of the conduit. Thus, it is seen the water in passing through the conduit will be filtered by the strainer and all 70 foreign matter removed before it is discharged into the drain pipe, and that the strainer is disposed at an angle to the flow of the water so it will pass therethrough, and yet is sufficiently inclined downwardly 75 from the trough to insure the washing-away 80 of the foreign matter collected thereby.

Since the foreign matter deposited on the strainer will have a tendency to cling thereto, a plurality of longitudinal slide bars 16 are secured to the top side of the strainer, being arranged in spaced parallel relation and extending approximately the length of the strainer. These bars are slightly raised to space the foreign matter from the strainer 85 and will insure the washing of the foreign matter down the bars and over the end of the strainer. The spaced angle bars 17 extending transversely across the bottom of the strainer are secured to the underside of 90 the strainer and sides of the conduit and assist the percolation of the water through the strainer. It is a known fact that the water will have a tendency to cling to the bottom 95 of the strainer, but on striking the bars 17 100 will drop into the conduit, thus facilitating the passing of the water through the strainer.

While in the drawing the strainer is shown constructed of wire mesh it is apparent 105 that equally good results could be obtained by using a perforated plate, grate or other filtering means.

It is to be understood that the form of my invention herewith shown and described is 110 to be taken as a preferred example of the same, and that certain changes in the shape,

size, and arrangement of parts may be resorted to without departing from the spirit of the invention or the scope of the subjoined claims.

5 Having thus described my invention, I claim:

1. A device of the character described comprising a conduit, a strainer diagonally disposed within said conduit, said conduit and strainer being inclined downwardly from the eaves trough and transversely extending cross bars secured to the underside of said strainer having a depending portion at right angles to said strainer.

10 2. In a device of the character described, the combination with an eaves trough having an opening, of a conduit having an open end secured to the trough at said opening and inclined downwardly therefrom, a strainer diagonally disposed within said conduit having its lower end flush with the edge of the conduit, spaced angle bars extending transversely across the underside of

said strainer, having one side depending at right angles thereto, and a discharge pipe 27 extending from the lower end of said conduit.

3. In a device of the character described, the combination with an eaves trough, of an open conduit having a wall at its lower end, 30 said conduit being inclined downwardly from the trough and having communication therewith, a strainer diagonally disposed within said conduit having its upper end flush with the bottom of the trough and its lower end flush with the upper edge of the end wall of the conduit, relatively wide flat longitudinal slide bars mounted on the top side of said strainer in spaced relation, spaced cross bars secured to the underside of 35 said strainer having a side depending at right angles to said strainer and a discharge pipe extending from the end wall of said conduit.

In testimony whereof I affix my signature.

FRANK F. WRIGHT.
